HEEL-SEAT FITTING MACHINE

Earl A. Bessom, Marblehead, Mass., assignor to
United Shoe Machinery Corporation, Paterson,
N. J., a corporation of New Jersey

Application May 25, 1934, Serial No. 727,511

18 Claims. (Cl. 12—31.5)

This invention relates to the manufacture of shoes and is illustrated as embodied in a heel-seat fitting machine.

In preparing shoes for the reception of wood heels it is customary to trim material from the margin of the heel-seat portion of a sole attached to a shoe thereby to reduce the heel-seat portion of the sole, and to form upon the sole a pair of heel-breast receiving shoulders which extends 10 transversely of the sole from the forward lateral portions of the reduced heel-seat portion. In order to provide a solid foundation for the heel the reduced heel-seat portion of the sole should be substantially complementary to the attaching 15 face of the heel to be attached to the shoe, sufficient material being removed from the sole to insure that the rim of the attaching face of the heel shall snugly engage the overlasted counter portion of the shoe upper. Moreover, the heel-breast receiving shoulders should snugly engage the breast of the heel positioned upon the shoe.

In one type of machine used in preparing soles for the reception of wood heels the heel-seat portion of the sole either before or after the formation of heel-breast receiving shoulders, is distorted and is reduced by a drag knife while so distorted.

In order to reduce the heel-seat portion of the sole of a shoe by the use of a machine of the type 30 above described to a shape complementary to the attaching face of a heel to be attached to the shoe it is desirable that the distorted heel-seat portion of the sole shall be clamped and that the heel-seat reducing knife shall cut the distorted 35 and clamped heel-seat portion of the sole without substantially displacing the same. If the clamped and distorted heel-seat portion of the sole is not held securely the shoulder-forming knives and the heel-seat reducing knives, especially when 40 dull, displace the heel-seat portion of the sole as they trim the same with the result that the heel-seat portion is not trimmed to the proper shape. It will thus be clear that the above-mentioned trimming cuts must be accurately controlled 45 during the heel-seat fitting operation in order to reduce the heel seats to the desired uniform shape.

With the above-mentioned circumstances in view and in accordance with a feature of this invention the illustrated machine is provided with a plate which has a U-shaped opening and is constructed and arranged to support the heel-seat portion of a sole, a member for forcing the margin of the heel-seat portion of the sole against the plate, and a bulger which is constructed and arranged to force the central part of the heel-seat portion of the sole through the opening and which comprises a working face terminating in a 50 U-shaped edge and an elongated rib the sole-

engaging portion of which is spaced from the U-shaped edge by a recess.

In the illustrated construction after the margin of the heel-seat portion of the sole has been clamped between the sole-supporting plate and the member which forces the margin of the heel-seat portion of the sole against the plate, the bulger is operated to cause its rib to force the central part of the heel-seat portion of the sole through the U-shaped opening, portions of the 10 sole which are located between the member and the rib being straightened out and tensioned as they envelope the working face of the bulger. As the sole-engaging face of the rib arrives in the plane of the bottom face of the plate along which 15 the cutting edge of a heel-seat reducing knife slides, the U-shaped edge of the bulger which is similar to but somewhat smaller than the U-shaped opening, forces the tensioned sole against the edge of the opening. With the above construction the heel-seat portion of the sole is effectively tensioned as it is distorted in the machine, the tendency of the heel-seat reducing knife to pull portions of the sole to be trimmed away from the bulger being practically eliminated 20 by providing the bulger with a recess which is positioned between the rib and the U-shaped edge of the bulger.

In order further to insure that the forward 30 end of the heel-seat portion of the sole shall be properly tensioned widthwise against the pressure of the heel-seat reducing and the shoulder-forming knives and in accordance with another feature of this invention the member of the illustrated machine which forces the margin of the 35 heel-seat portion of the sole against the sole-supporting plate comprises a pair of parts which move laterally of the sole upon the plate as they are forced against the sole.

These and other features of the invention including certain details of construction and combinations of parts will be described as embodied in an illustrated machine and pointed out in the appended claims.

In the drawings,

Fig. 1 is a perspective view of the operating head of the illustrated machine in the process of fitting an attached sole of a shoe for the reception of a heel;

Fig. 2 is a side view of the machine illustrated in Fig. 1 the greater part of which is shown in section;

Fig. 3 is an illustrative view showing the relation of the heel-seat reducing knife and the 55 clamped heel-seat portion of the sole during the first part of the heel-seat reducing operation;

Fig. 4 is a perspective view of a sole-supporting plate of the machine;

Fig. 5 shows in perspective a portion of the 60

mechanism for clamping the margin of the heel-seat portion of the sole against the plate;

Fig. 6 is a perspective view of the bulger which forces the central part of the heel-seat portion of the sole clamped to the plate through a U-shaped opening formed in the plate; and

Fig. 7 is a perspective view of the rear end of the sole of an inverted shoe after it has been operated upon in the above machine.

The illustrated machine is described with reference to trimming the heel-seat portions of soles attached to shoe uppers for the reception of wood heels. As above stated it is customary to trim the margin of the heel-seat portion of a sole 20 attached to a shoe upper 22 by a beveling cut and by a transverse cut or cuts in order to reduce the heel seat (as shown at 24 in Fig. 7) thereby providing a beveled margin 26 and a pair of heel-breast receiving shoulders 28 at the forward end of the heel seat. The central part 30 of the reduced heel seat is substantially flat and may be referred to as the plateau portion, the sole-engaging face of the reduced heel seat 24 being substantially complementary to the attaching face of the heel which is to be secured to the shoe. The edge 32 of the reduced heel seat 24 should extend almost to the rim of the attaching face of the heel in order to insure that the margin of the attaching face of the heel shall be well supported by the sole and shall receive the nails which attach the heel to the shoe. It is desirable, however, that an amount of stock sufficient to insure that the rim of the attaching face of the heel shall snugly engage the counter portion of the shoe upper shall be removed from the heel-seat portion of the sole.

As above stated, in one type of heel-seat fitting machine the heel-seat portion of the sole is reduced by one or more knives while it is held in a distorted condition. A machine of this general type is disclosed in United States Letters Patent No. 1,980,371, granted November 13, 1934 on an application filed in my name, in which machine construction illustrated herein may be readily incorporated in place of detachable portions of the machine. Accordingly, only portions of the machine believed to be essential in illustrating this invention are described herein since a complete understanding of the construction and operation of the machine as a whole may be obtained by reference to the above-mentioned United States Letters Patent.

The sole of the shoe is supported upon a crease plate 34 provided with a U-shaped opening 36 (Fig. 4) defined by a thin edge 38 which is formed by a beveled face 40 and a planar underside of the plate 34. The frame 42 (Fig. 1) of the machine is slotted in order interchangeably to receive one of a plurality of plates 34 having U-shaped openings 36 of different sizes, the plates being held in position in the machine through the provision of a spring-pressed pin 44. The sole may be positioned lengthwise and laterally upon the plate by a back gage 46 and a V-shaped gage 48, respectively, against which the rear counter portion of the shoe is forced. The back gage 46 and the V-shaped gage 48 are normally forced forwardly of a stop 50 under spring pressure, the stop being set in predetermined position in accordance with the size of the heel to be attached to the shoe as disclosed at length in said United States Letters Patent No. 1,980,371.

In order to press the margin of the heel-seat portion of the sole against the beveled face 40 of the plate 34 preparatory to distorting the

same by a bulger 52, the illustrated machine is provided with a U-shaped presser member which includes a bight portion 56, a pair of arm portions 58, and a spreader 60. For convenience of description the bight portion 56 and the arm portions 58 will be referred to as a back clamp 57. The bight and the arm portions 56 and 58 of the back clamp 57 are provided with inserts 62, 64 which may be made of rubber or of other suitable yielding material. The bight portion 56 is movable relatively to the arm portions 58 during the sole-clamping operation as will later be explained in order that the margin of the heel seat which usually varies in thickness may be effectively clamped against the plate 34.

The inserts 64 of the arms 58 are included within metal walls 66 formed integral with a slide 68 which is constructed and arranged for reception within opposed grooves 70 (Fig. 1) of a housing 72. The insert 62 of the bight portion 56 of the back clamp 57 is also included within metal retaining walls 74 which are pivotally mounted upon a pin 76 supported in lugs 78 of the slide 68.

Secured by screws 80 (Fig. 1) to the forward end of the housing 72 is a rectangular frame 82 provided with a guideway 84 in which a bifurcated block 86 is mounted for vertical movement, the block being bored to receive a strong spring 90 which normally retains the block 86 at the bottom of the guideway 84. The spreader 60 is pivotally mounted upon a bearing 92 which is in threaded relation with the block 86, presser feet 101 of the spreader 60 being normally urged toward each other by a spring 94 the opposite ends of which are secured to pins 96 mounted upon extensions 98 and 100 of the spreader 60, respectively. In order to limit the movement of the presser feet 101 of the spreader 60 toward each other the extension 98 carries an adjustable screw 102 which, when the housing 72 is raised and the presser feet 101 are moved together under tension of the spring 94, engages the extension 100. The sole-engaging faces 104 of the presser feet 101 are serrated for gripping the sole firmly. The sole-engaging faces 104 of the spreader 60 may be arranged to lie in substantially the same plane as the sole-engaging faces of the arm portions 58 or may extend slightly below the same in order to lead the arm portions 58 during the sole-clamping operation.

The bulger 52 is provided with a recess 106 shaped and arranged to receive a stud 108 projecting downwardly from a flange portion 110 (Fig. 2) of a bulger-operating rod 112 which is mounted for sliding movement along a cylindrical recess of an extension 114 of the housing 72. The extension 114 of the housing 72 is positioned for reciprocation within a bore of a boss portion 116 of the frame of the machine. The bulger 52 is reciprocated in a vertical path by a collar 118 which is operated by mechanism clearly disclosed in the above-mentioned United States Letters Patent No. 1,980,371. The housing 72 is normally forced into engagement with the flange portion 110 of the bulger-operating rod 112 by a spring 120 which surrounds the rod 112 and is enclosed within a cylindrical housing 122 secured to the rod. The first part of the downward movement of the rod 112 causes the spring 120 which engages the upper end of the extension 114 of the housing 72 to force the U-shaped presser unit against the margin of the heel-seat portion of the sole positioned upon the plate, further downward movement of the rod causing the springs 120 to

be compressed by the cylindrical housing 122 and thus causing the bulger 52 to be forced through the U-shaped opening 36 of the plate 34. A face 124 (Fig. 6) of the bulger 52 is positioned about a quarter of an inch above the lower sole-engaging face of the rubber inserts, 62, 64 of the back clamp 57 when the machine is at rest with the flange portion 110 in engagement with the housing 72.

10 The back clamp 57 is mounted for rocking movement as a unit. This is effected by flaring the opposed grooves 70 rearwardly of the housing from their forward ends, the plate being normally forced into engagement with the lower 15 sides of the grooves 70 by a spring-pressed plunger 128 (Fig. 2) which engages the rear upper portion of the slide 68. The bight portion 56 of the back clamp 57 is normally forced beyond the arm portion 58 by a pair of springs 130. Pivotal 20 movement of the bight portion 56 is limited by pins 132 carried by the respective arm portions 58 and operating in elongated slots 134 of the bight portion 56.

Opposing portions of the forward faces of the recess 106 (Fig. 2) and the stud 108, respectively, are flattened in order to insure that the bulger shall not turn upon the stud 108. The bulger 52 is retained upon the stud 108 by a spring-pressed plunger 136 which normally engages within a 30 concavity in the front face of the stud 108.

In view of the foregoing it will be clear that as the rod 112 is lowered it causes the housing 72 yieldingly to force the U-shaped presser unit against the margin of the heel-seat portion of 35 the sole upon the plate 34. As the back clamp 57 engages the sole the rear end of the slide 68 rocks upwardly and the bight portion 56 also swings relatively to the arm portions 58 about the pin 76 thereby insuring that substantially the 40 entire margin of a sole of non-uniform thickness is securely pressed against the beveled face 40 of the plate 34. Moreover, since the sole-engaging portions 62, 64 (Fig. 5) of the bight and the arm portions 56 and 58, respectively, are constructed of rubber such portions conform to a 45 considerable extent to the shape of the sole being clamped in the machine.

It is desirable, especially when knives 138 (Fig. 2) which form the heel-breast receiving shoulders 28 (Fig. 7) move at right angles to the general plane of the sole, that the forward part of the heel-seat portion of the sole be stretched under considerable tension in order to avoid displacing the sole during the shoulder-forming operation. By providing the spreader 60 the serrated faces 104 of which move apart as they are forced against the sole, the forward end of the heel-seat portion of the sole is securely held in place as the knives 138 form the heel-breast receiving shoulders 28 and also as a knife 140 moves forwardly of the sole in engagement with the under side of the plate 34 to reduce the heel-seat portion of the sole.

The plate 34 is provided with forward planar surfaces 142 which serve as effective beds along which the sole slides as the serrated faces 104 of the spreader 60 tension the sole laterally.

After the sole has been clamped in the machine the shoulder-forming knives 138, which are movable with the bulger 52, are lowered to form the heel-breast receiving shoulders 28. The shoulder-forming knives 138 are given a slight lead over the bulger 52 in order to insure that the shoulders 28 are formed before the heel-seat portion of the sole is distorted substantially. The sole is

therefore practically undistorted forwardly of the heel-breast line 144 (Fig. 7) of the shoe during the heel-seat fitting operation.

As above stated in order to control the shape of the reduced heel seat 24 formed in a machine of the type above mentioned the displacement of the heel-seat portion of the clamped sole by the shoulder-forming knives 138 and the heel-seat reducing knife 140 should be reduced to a minimum. It frequently happens that the shoulder-forming knives 138, especially when dull, force the central part of the sole in the vicinity of its breast line 144 a considerable distance below the crease plate 34. When this happens the heel-seat reducing knife 140 in moving along the lower 10 face of the plate 34 reduces the heel seat in such a way that its plateau portion 30 increases in width as it approaches the heel-breast line 144 and is so wide that it prevents the forward end of the rim of the attaching face of the heel from engaging the overlusted counter portion of the shoe upper. This difficulty has been largely overcome by providing the above spreader 60 which tensions the forward end of the heel-seat portion of the sole laterally. The outline to which the heel 20 seat is reduced is determined by the shape of the thin edge 38 and it is therefore desirable that the heel-seat portion of the sole be effectively tensioned and forced against the edge 38 preparatory to trimming the sole. Moreover, the beveled 25 margins 26 should be of considerable width in order that the reduced heel seat shall be of a shape which is practically complementary to that of the attaching face of the heel. The size of the plateau portion 30 of the sole is determined 30 by the length of the beveled margin 26. It is desirable that the outline of the reduced heel seat 24 and the length of the beveled margin 26 be varied in accordance with the heel to be attached to the shoe and with this in view it is customary 35 to change the crease plate 34 and the back clamp 57 from time to time. It has been found by experience that three complete sets of parts are sufficient.

In order to insure that the heel-seat portion 45 of the sole held against the plate by the U-shaped presser unit is properly tensioned and is forced with considerable pressure against the edge 38 of the U-shaped opening 36, the working side of the bulger 52 comprises a planar face 146 (Fig. 6) which terminates in a U-shaped edge 148, and a rib 150 provided with a U-shaped edge 152 which is spaced from the edge 148, the rib projecting beyond the planar face 146. The sole-engaging face 124 of the rib 150 corresponds 50 substantially to the shape of the plateau portion 30 of the reduced heel seat to be formed. A re-entrant angle or recess 154 is thus included between the edge 152 and the edge 148 of the bulger, the sole bridging the recess during the 55 heel-seat fitting operation. The sole-engaging face 124 and the U-shaped edge 148 of the bulger 52 may be said to be spaced from each other by a reentrant portion of the bulger. Although a reentrant angle 154 is illustrated it will be understood that the reentrant portion, if desirable, may have other shapes. The working face of the bulger may thus be described as terraced or stepped. The U-shaped sole-engaging edges 148 and 152 of the rib 150 and the face 146, respectively, are arranged in substantially similar relation and lie in parallel planes.

When the bulger 52 is lowered the sole is engaged by the rib 150, the heel-seat portion of the sole which is held against the plate 34 by the 60

When the bulger 52 is lowered the sole is engaged by the rib 150, the heel-seat portion of the sole which is held against the plate 34 by the 65

When the bulger 52 is lowered the sole is engaged by the rib 150, the heel-seat portion of the sole which is held against the plate 34 by the 70

When the bulger 52 is lowered the sole is engaged by the rib 150, the heel-seat portion of the sole which is held against the plate 34 by the 75

clamping unit being tensioned. The U-shaped edge 148 at this time is out of contact with the heel-seat portion of the sole. Just before the sole-engaging face 124 of the rib 150 is lowered 5 into substantial alinement with the lower face of the plate 34 the U-shaped edge 148 engages the tensioned heel-seat portion of the sole and causes the same to be forced with considerable pressure against the edge 38. As above stated, 10 in order to control the shape to which the heel seat is cut it is not only desirable to hold the heel-seat portion of the sole under tension but it is also desirable to reduce as much as possible the tendency of the heel-seat portion of the sole 15 to resist the cutting pressure of the heel-seat reducing knife 140. It has been found by experience that as the knife 140 (Fig. 3) engages the rear end of the distorted sole there is a tendency for the knife to bunch the leather ahead 20 of it and to pull the sole away from the bulger 52. Such a tendency makes it difficult to locate with any degree of accuracy the rear end of the 25 plateau portion 30 where the knife initially cuts through the sole and usually causes the plateau portion 30 to be wider than desirable and to flare toward its forward end, this being objectionable for reasons above explained. When the heel-seat portion of the sole being cut is once pulled away from the bulger 52 the greater becomes the tendency for the knife to pull the sole 30 further away from the bulger 52 and for this reason it is especially desirable to prevent the knife from initially displacing the sole. In the 35 illustrated construction the knife 140 in starting the heel-seat reducing cut moves forwardly along the path 156 (Fig. 3), the sole being flexed toward the bulger 52 and entering the recess portion 154 under the operating pressure of the knife. With such a construction the displacement of the heel-seat portion of the knife 140 40 is reduced to a minimum, the knife passing along the surface 124 and cooperating with the rear portion of the edge 152 to trim the sole by a shearing cut. As the knife 140 progresses forwardly of the sole the heel-seat reducing cut extends from the edge 152 to the edge 38 of the plate 45 34. By providing the recess 154 it has been found that even though the knife 140 is slightly dull the heel-seat reducing cut follows around the edge 152 of the rib 150 and therefore forms 50 a wide bevel which corresponds to the distance from the edge 152 to the U-shaped edge 38 of the opening. With such a construction it is possible by properly shaping the working side 55 of the bulger and the shape of the U-shaped opening 36 accurately to control the shape of the reduced heel-seat to be formed. The bulger 52 may be advantageously used with various types of presser members which effectively clamp 60 the margin of the heel-seat portion of the sole against the crease plate.

The shoulder-forming and the heel-seat reducing knives 138, 140, respectively, may be operated by mechanism such as described in the 65 above-mentioned United States Letters Patent No. 1,980,371. The knife 138 may be operated to form the heel-breast receiving shoulders 28 either before or after the heel-seat portion of the sole has been reduced.

In order to perform the heel-seat fitting operation the operator positions the sole of the shoe 70 upon the plate 34 and then steps on a treadle (not shown) thereby causing the margin of the heel-seat portion of the sole to be forced against the plate. Further movement of the treadle

which is effected by power-operated mechanism causes the sole to be forced with considerable pressure against the plate 34 and also causes the bulger 52 to force the central part of the heel-seat portion of the sole through the U-shaped 5 opening 36. The shoulder-forming knives 138 are moved with the bulger and are given a small lead in order to form the heel-breast receiving shoulders 28 prior to any substantial distortion of the heel-seat portion of the sole. The knife 10 140 then moves forwardly of the sole automatically to reduce the heel-seat portion of the same. The shoulder-forming knives 138 are usually retained in the shoulder-forming incisions in order to serve as anvils against which the knife 15 140 operates, thereby preventing the work from being pushed forwardly away from the knife at the end of the heel-seat fitting operation, all of which is clearly described in said United States Letters Patent No. 1,980,371. 20

Having described my invention, what I claim as new and desire to secure by Letters Patent of the United States is:

1. In a heel-seat fitting machine, a plate provided with an opening, a member for pressing the 25 margin of the heel-seat portion of a sole against the plate, and a bulger for forcing the central part of said heel-seat portion through the opening, said bulger comprising sole-engaging portions spaced by a recess which is bridged by 30 the tensioned heel-seat portion of the sole when the central part of said heel-seat portion has been forced through the opening.

2. In a heel-seat fitting machine, a plate provided with an opening, a member for pressing the 35 margin of the heel-seat portion of a sole against the plate, and a bulger for forcing the central part of the heel-seat portion of the sole through the opening, said bulger being constructed and arranged to engage only the median part of said 40 heel-seat portion and parts of the heel-seat portion which are positioned near the edge of the opening thereby to cause an intermediate area of said heel-seat portion to be held out of contact with the bulger. 45

3. In a heel-seat fitting machine, a plate having a U-shaped opening, a member constructed and arranged to press the heel-seat portion of a sole against the plate, and a bulger provided with a U-shaped edge included in a plane and having a 50 rib which projects beyond the plane of said edge and has a sole-engaging face spaced from said edge by a reentrant portion, means constructed and arranged to force the pressing member against the margin of the heel-seat portion of the sole supported by the plate, and means for operating the bulger to cause the rib to force the median part of the heel-seat portion of the sole through the U-shaped opening thereby tensioning the clamped sole about the bulger and to 55 cause the U-shaped edge to force the tensioned sole against the edge of the U-shaped opening.

4. In a heel-seat fitting machine, a plate provided with a U-shaped opening, a member to press the margin of the heel-seat portion of a 65 sole against the plate, and a bulger which comprises a face terminating in a U-shaped edge which is slightly smaller than the U-shaped opening, said bulger also comprising a rib projecting from the median portion of said face and extending lengthwise of the U-shaped edge. 70

5. In a heel-seat fitting machine, a plate having a U-shaped opening, a clamp for pressing the margin of the heel-seat portion of a sole against the plate, and a bulger provided with a U- 75

shaped edge and having a rib which extends lengthwise of the U and has a sole-engaging face which is spaced from the U-shaped edge by a reentrant portion, said rib being constructed and arranged to force the median part of the heel-seat portion of the sole which is pressed against the plate by said clamp through said opening thereby to tension the same about the bulger before the U-shaped edge forces the sole against the edge of said opening, and means for operating said clamp and said bulger.

6. In a heel-seat fitting machine, a plate provided with an opening, a clamp for forcing the margin of the heel-seat portion of a sole against the plate, and a bulger for forcing the central part of the heel-seat portion through the opening, said bulger having a stepped work-engaging face.

7. In a heel-seat fitting machine, a plate provided with a U-shaped opening, a clamp for forcing the margin of the heel-seat portion of a sole against the plate, and a bulger having a working face terminating in a U-shaped edge and having an elongated rib the sole-engaging portion of

25 which is spaced from said edge by a recess.

8. In a heel-seat fitting machine, a plate provided with a U-shaped opening, a clamp for forcing the margin of the heel-seat portion of a sole against the plate, and a bulger having a working face including a planar U-shaped edge which is smaller than the opening and a projecting median portion a sole-engaging face of which is spaced from said edge by a reentrant portion.

9. A heel-seat fitting machine having, in combination, a support provided with a U-shaped opening, a member for pressing the margin of the heel-seat portion of a sole against the support, a bulger for forcing the central part of the heel-seat portion through the opening, and means 40 for moving the bulger in a predetermined path toward and from the support, said bulger comprising a pair of U-shaped edges which are of different sizes and are spaced from each other in the general direction of said path.

45 10. A heel-seat fitting machine having, in combination, a support provided with a U-shaped opening, a member for pressing the margin of the heel-seat portion of a sole against the plate, and a bulger for forcing the central part of said heel-seat portion through the opening, said bulger comprising a pair of planar U-shaped edges of different sizes arranged in stepped relation.

11. A heel-seat fitting machine having, in combination, a plate provided with an opening, a member for pressing the margin of the heel-seat portion of a sole against one side of the plate, a bulger for forcing the central part of said heel-seat portion through the opening and beyond the other side of the plate, a knife provided with a cutting edge movable along said other side of the plate to reduce the heel-seat portion of the sole, said bulger being constructed and arranged to engage only the median part of the heel-seat portion and parts of the heel-seat portion which are positioned near the edge of the opening thereby to cause areas of the heel-seat portion which are included between said parts to be held out of contact with the bulger as the knife cuts the sole.

70 12. In a heel-seat fitting machine, a plate provided with an opening, a clamp for forcing the margin of the heel-seat portion of a sole against the plate, and a bulger for forcing the central part

of the heel-seat portion through the opening, said bulger comprising a pair of U-shaped sole-engaging portions of different sizes arranged in similar relation and lying in spaced parallel planes respectively.

5 13. In a heel-seat fitting machine, a plate provided with a U-shaped opening, a clamp for forcing the margin of the heel-seat portion of a sole against the plate, said clamp comprising means for tensioning said heel-seat portion 10 widthwise as it forces said margin against the plate, a bulger having a working face terminating in a U-shaped edge and comprising an elongated rib the sole-engaging portion of which is spaced from said edge by a recess, means for operating 15 the clamp and the bulger, and means for reducing the heel-seat portion of the sole.

14. In a heel-seat fitting machine, a plate for supporting the heel-seat portion of a sole, and means for clamping the margins of the heel-seat 20 portion of the sole against the plate, said means comprising a spreader constructed and arranged to tension the forward part of the heel-seat portion of the sole widthwise.

25 15. A heel-seat fitting machine having, in combination, a sole-supporting plate provided with an opening, clamping means constructed and arranged to force the margin of the heel-seat portion of a sole against said plate, said clamping means comprising a spreader for tensioning the 30 heel-seat portion of the sole as it is pressed against the plate, means for forming heel-breast receiving shoulders upon the sole, a bulger for forcing the central part of the heel-seat portion of the sole through the opening, and means for 35 reducing the heel-seat portion of the sole.

16. A heel-seat fitting machine having, in combination, a plate provided with a face for supporting the heel-seat portion of a sole, a member mounted for movement in a path disposed at a 40 substantial angle to said surface, a clamp mounted for movement with said member for forcing portions of the margin of the heel-seat portion of the sole against the plate, and a pair of presser feet carried by said member, said presser feet 45 being constructed and arranged to yield relatively to said member when forced into engagement with the sole and to move away from each other to tension the forward part of the heel-seat portion of the sole widthwise.

50 17. A heel-seat fitting machine having, in combination, a plate for supporting the heel-seat portion of a sole, means mounted for movement relatively to the plate to clamp the margin of the heel-seat portion of the sole against the plate, 55 and mechanism for operating said means, said means including presser members which are mounted for yielding movement relatively to said mechanism and are constructed and arranged to tension the forward part of the heel-seat portion 60 of the sole widthwise as they are forced against the sole positioned upon the plate.

18. A heel-seat fitting machine having, in combination, a plate for supporting the heel-seat portion of a sole, and means for clamping the margin 65 of the heel-seat portion of the sole against the plate, said means comprising a pair of pivotally mounted presser feet which are normally urged together and which separate as they are forced against the sole positioned upon the plate thereby 70 to tension the forward part of the heel-seat portion of the sole widthwise.

EARL A. BESSOM.
